Primary Examiner — Richard Edgar*Assistant Examiner* — Cheng Chen(74) *Attorney, Agent, or Firm* — Latimer LeVay Fyock LLC(57) **CLAIM**

The ornamental design for a label as shown and described.

DESCRIPTION

FIG. 1 is a perspective view of the label in place on a container;

FIG. 2 is an elevational view of the front of the label, the top, bottom, left side, right side and back being unadorned;

FIG. 3 is a perspective view of a second embodiment of the label in place on a container; and,

FIG. 4 is an elevational view of the front of the second embodiment of the label, the top, bottom, left side, right side and back being unadorned.

The broken line showing is included for the purposes of illustrating portions of the article and its placement, and forms no part of the claimed design.

1 Claim, 4 Drawing Sheets(56)
